DOWNWARD STROKE AIR EVACUATING JAR
SEALING APPARATUS

Halton A. Billeter, Youngstown, Ohio

Application December 31, 1943, Serial No. 516,575

5 Claims. (Cl. 226—82)

1

This invention relates to method and apparatus for vacuum sealing containers such as food preserving jars and cans, for example. It has heretofore been proposed to provide on the top end of the container to be sealed an annular surface against which may be applied the outer rim portion of a lid or cover and it has also been proposed to evacuate the space above the food in the container and the surface immediately about the lid or cover itself preparatory to the final seating of the lid or cover so that upon removal of the evacuating apparatus the atmospheric pressure will hold the lid firmly on the container. To insure proper functioning of this method the lid is normally provided with a soft pliable ring or gasket which fits the annular seating surface on the container thereby providing a fluid-tight connection.

The specific methods heretofore devised for effecting the above described sealing operation have required either costly apparatus or apparatus which is difficult and cumbersome to manipulate. It is accordingly the primary object of the invention to provide an improved and simplified method for evacuating the air from a container immediately prior to the final seating of a fluid-tight closure thereon; and improved and simplified apparatus for effecting this mode of operation. To this end I provide a unitary and compact device which, in use, is merely placed on the upper end of the jar or container to be sealed to encompass the closure member and which is provided with an operating member which requires but one or a few downward strokes to effect the required evacuation of the jar or container. In this manner the sealing operation is very materially simplified which is of further advantage when the container and contents is hot when sealed since the operation may be completed before the same cools appreciably and since any necessity for the operator handling the container is eliminated.

A further object of the invention is the provision of an improved apparatus having utility as pointed out above which is readily adaptable for use in connection with preserving jars or containers of different configurations and designs.

The above and other objects and advantages of the invention will become apparent upon consideration of the following detailed specification and the accompanying drawing wherein there is disclosed certain preferred embodiments of the invention.

In the drawing:

Figure 1 is a vertical section through a vacuum

2

sealing device constructed in accordance with the principles of the invention, the view showing the device as being operatively applied to a preserving jar of the "Mason" type;

Figure 2 is a fragmentary vertical section of a modified form of sealing device for use on a preserving jar of the "Perfect seal" type, for example; and

Figure 3 is a bottom view of the apparatus of Figure 1.

In the drawing, reference numeral 10 indicates a cylinder having an upper end wall 11 and screw threads on its outer surface adjacent its lower end. A number of circumferentially spaced apertures 12 are formed in the side wall of the cylinder 10 above the screw threads thereon. Screw threaded onto the lower end of the cylinder 10 is a member having a transverse wall 13 constituting the lower end wall of the cylinder 10. This member is also provided with a depending flange which is in general continuation of the outer surface of the cylinder 10 and in Figure 1 this flange, shown at 14, is elongated so as to reach past the threads on the jar 15 and engage the annular shoulder 16 provided on jars of the type illustrated. To the lower end of the flange 14 is secured a soft pliable ring 17 which with the upper surface of the shoulder 16 forms a fluid-tight connection.

It should be observed that the flange 14 is of sufficient length to provide space intermediate the upper annular surface 18 of the jar and the horizontal wall 13 for the loose reception of the jar sealing closure or lid. This lid, indicated by reference numeral 19, may be a thin disk of metal having a depressed center portion to provide an annular recess in which is secured a soft pliable sealing ring 20. The outer peripheral wall of the depressed portion also serves as a guide to insure the proper seating of the lid on the jar. Extending downwardly from the bottom surface of the wall 13 are a number of segmental bosses 21 and extending upwardly from the center of the wall 13 is an elongated boss 22 preferably integral with the wall 13.

Slideable in the cylinder 10 is a piston 23 to which is connected a plunger 24 extending up through an opening in the top end wall 11 of the cylinder 10. A close fit is provided between the plunger 24 and the aperture through wall 11 so as to minimize leakage of air. To the upper end of plunger 24 is fastened a knob 25 the upper surface of which together with the upper end of the plunger 24 is curved slightly to fit comfortably against the palm of the hand of the

person using the apparatus. Depending from the center portion of the piston 23 and preferably integral therewith is a sleeve 26 which is adapted to have a close sliding fit over and about the outer surface of the boss 22. Extending longitudinally through the boss 22 and the wall 13 is a bore 21 and another passageway 28 located partly in the plunger 24 provides communication between the upper end of the cylinder formed by the sleeve 26 and the space in cylinder 10 above the piston 23. Encircling the sleeve 26 and the boss 22 is a coil spring 29 the function of which is to normally bias the plunger 24 and piston 23 to uppermost position.

Since a close fit is provided between the plunger 24 and the aperture in the top end wall 11 of the cylinder 10 as well as between the piston 23 and the cylinder 10 downward movement of the piston in the cylinder will decrease the pressure in the space above the piston 23 causing air to be drawn into the space through the passageways 27 and 28. If now the apparatus is placed on a jar or other container with the sealing ring 17 maintained in fluid-tight engagement therewith, the suction created by the expanding chamber caused by the downward movement of the piston 23 will withdraw a substantial part of the air contained within the jar or other container, such withdrawn air passing up through the openings 27 and 28 and into the expanding chamber above the piston 23.

In employing the apparatus described above to effect the vacuum sealing of the jar 15 the lid 19 is first laid loosely in proper position on the jar after which the assembled apparatus described is placed on the jar in the position shown in the drawing. Next, the palm of the hand is laid on the knob 25 and by a quick downward thrust the air within the jar 15 above the food or other contents therein and within the housing formed by the wall 13 and flange 14 will be evacuated into the cylinder 10 above the downwardly moving piston 23 through the passageways 27 and 28 as explained above. The air displaced below the piston 23 escapes through ports 12. During this operation the lid 19 acts as a valve and raises slightly to allow the air to escape from within the jar 15. The spaces circumferentially intermediate the segmental bosses 21 insure the continuance of communication between the space within the jar and the bore 27 even though the lid 19 is drawn up into tight engagement with the lower surface of the bosses 21 as shown in the drawing. Immediately upon cessation of movement of the piston 23 and the consequent cessation of outflow of air from the jar 15 the lid 19 seats by force of gravity and back pressure on the surface 18 of the jar so as to preserve the vacuum created in the jar. The spring 29 now returns the piston 23 to its upper or initial starting position and the atmospheric pressure then coming against the outer surface of the lid 19 firmly holds the lid on the jar.

It should be observed that upon the application of downward force to the knob 25 the apparatus will be urged downwardly as a whole thus bringing the sealing ring 17 into pressure engagement with the shoulder 16 of the jar 15 thus effecting an efficient seal against the entrance of outside air into the member 14. As the piston 23 moves downwardly against the force of the spring 29, the air within the jar and within the member 14 is sucked into the space in chamber 10 above piston 23 thus at least partially evacuating the air from within the jar 15. Upon the

piston 23 reaching the lower end of its stroke and the subsequent release of the downward pressure applied to the knob 25, the spring 29 begins to move the piston 23 upwardly thus reversing the flow of air in the passageway 27 and, as explained above, this back pressure, as well as the force of gravity, will quickly seat the lid 19 on the surface 18 of the jar 15. The withdrawal of external downward force on the apparatus reduces the seal at the ring 17 so that if the pressure developed in member 14 immediately outside of the lid 19 by continued upward movement of the piston 23 in the cylinder 10 becomes greater than atmospheric pressure, the excess air will bleed off under the ring 17. Thus, the apparatus acts as an efficient air suction pump and a number of successive downward movements of the plunger and piston may be applied to further evacuate the jar if desired. In the normal and convenient operation of the device, such successive downward thrusts are applied rapidly in succession. This rapid operation can be accomplished only by withdrawing all outwardly applied pressure during the return movement of the plunger and piston and the mode of operation concerning the release of the excess air as explained above is accomplished.

An important feature of the invention is the obtaining of a high degree of vacuum by downward movement of the plunger. This arrangement enables the required connection between the apparatus and the jar or container to be sealed to be effected simply by seating the apparatus on the jar or container. Further, upon downward pressure being applied to the apparatus through the plunger and piston the apparatus is automatically brought into pressure engagement with the jar or container thus automatically effecting an efficient seal between the jar or container and the evacuating housing against the ingress of air. In this manner the device is made highly efficient in operation.

Another important advantage of the invention is the facility with which the apparatus may be modified in the hands of the user to operate efficiently on preserving jars of different types. In Figure 2, for example, there is illustrated a modified form of jar 30 which is in common use and this jar is provided with a wide flat annular top surface 31. For this jar the sealing lid, indicated by reference numeral 32 in Figure 2, may be of such diameter that its outer edge occupies only about half the radial width of the surface 31, thus allowing the outer peripheral portion of the surface 31 to be engaged by the lower end of the evacuating housing of the assembled apparatus. In modifying the apparatus of Figure 1 for use in connection with jars of the type shown in Figure 2 the housing or member including the flange 13 is replaced by a member or housing which is generally similar but which has a much shortened flange 33. It should be observed that in any of the embodiments of the invention the space within the housing of the apparatus which is in communication with the space within the jar during the evacuating process is of minimum volume so that a high degree of vacuum can be obtained from the first downward thrust on the plunger of the apparatus and in most cases a single downward thrust will be sufficient. This depends, of course, on the extent to which the jar is filled with solid or liquid materials.

It should now be apparent that I have provided an improved method of evacuating a jar

or container during the sealing thereof and that I have provided improved apparatus for accomplishing this object. The apparatus is simple and compact in design and may readily be economically produced in large quantities principally by casting in metal or plastics and is rugged and durable in use. The advantages of evacuating and sealing the jar or container while the same and its contents are still quite hot are well recognized in the art and the nature and mode of operation of the present method and apparatus enables the evacuating and sealing to be accomplished in a very short interval of time while eliminating any necessity for holding or otherwise manipulating the hot jar or container. It is only necessary to place the latter on a solid surface after which the lid and evacuating apparatus can be set on in the manner outlined above.

The above specifically described embodiments of the invention should be considered as illustrative only as obviously many changes may be made therein without departing from the spirit or scope of the invention. Reference should therefore be had to the appended claims in determining the scope of the invention.

What I claim is:

1. Vacuum sealing apparatus comprising in combination a fluid-tight housing having an annular lower end adapted to be brought into fluid-tight engagement with an annular surface on the upper portion of a jar to be sealed, said housing being adapted to contain a sealing lid for said jar, a cylinder connected to and extending upwardly from said housing, said cylinder having an upper end wall, a piston in said cylinder, a plunger having an upper palm engageable surface slideably mounted in said upper end wall and connected to said piston, and means providing communication between the space within said housing and the space in said cylinder above said piston whereby upon downward movement of said plunger the air within said housing and jar will be evacuated.

2. Vacuum sealing apparatus comprising in combination a fluid-tight housing having an upper wall and an annular lower end adapted to be brought into fluid-tight engagement with an annular surface on the upper portion of a jar to be sealed, said housing being adapted to contain a jar sealing lid, a cylinder connected to and extending upwardly from said housing, said cylinder having an upper end wall, a piston in said cylinder, a plunger having an upper palm engageable surface slideably mounted in said upper end wall and connected to said cylinder, said housing having an upwardly extending boss, said piston having a sleeve slideably received over said boss, an opening extending longitudinally through said boss and upper wall of said housing, and means providing communication between the space within said sleeve and the space within said cylinder above said piston whereby downward movement of said plunger and piston results in evacuation of the air within said housing and jar.

3. Apparatus of the character described for use with a container having an upwardly facing annular surface and a free seating closure member adapted to seat over an opening in said container

radially inward of said surface comprising in combination a fluid-tight housing having a depending flange adapted to rest in fluid-tight engagement on said surface, a cylinder connected to and extending upwardly from said housing, said cylinder having a top end wall, a manually engageable plunger extending through said wall, a piston in said cylinder connected with said plunger, and means providing communication between the space within said housing and the space in said cylinder above said piston whereby upon downward movement of said plunger the air within said housing and container will be evacuated.

4. Evacuating apparatus for use with an open-topped container and a self-sealing lid for closing and sealing said container comprising in combination a fluid impervious housing having a flange adapted to be brought into fluid-tight engagement with a surface of said container outwardly of said lid, a fluid pump carried by said housing and including a member reciprocable in a vertical direction and operable upon quick downward movement to evacuate the space below and about said lid, said member having a single upper surface of appreciable area for being comfortably engaged by the palm of a user's hand and having a path of movement generally coincident with the vertical axis of said container, the arrangement being such that the downward thrust applied to said member simultaneously increases the pressure of said engagement and effects said evacuation.

5. Evacuating apparatus for use with an open-topped container and a self-sealing lid for closing and sealing said container comprising in combination a fluid impervious housing having a flange adapted to be brought into fluid-tight engagement with a surface of said container outwardly of said lid, a fluid pump comprising relatively slideable piston and cylinder members one of which is rigidly connected with said housing and the other of which is provided with a single circular concaved but generally horizontal upper surface of appreciable area positioned centrally above said container and being adapted to be comfortably engaged by the palm of a user's hand whereby said other member may be rapidly moved downwardly, spring means for moving said other member upwardly, and a passageway in the said one of said members interconnecting the space within said flange with the space within that end of the cylinder which is increased in volume upon downward movement of said other member.
